CLAIM

We claim the ornamental design for a clip for hearing aid, as shown and described.

DESCRIPTION

FIG. 1 is a perspective view of a clip for hearing aid embodying our design;

FIG. 2 is a side elevational view of the clip for hearing aid shown in FIG. 1;

FIG. 3 is a rear view of the clip for hearing aid shown in FIG. 1;

FIG. 4 is a top view of the clip for hearing aid shown in FIG. 1;

FIG. 5 is an opposite side elevational view of the clip for hearing aid shown in FIG. 2;

FIG. 6 is a bottom view of the clip for hearing aid shown in FIG. 1;

FIG. 7 is a front view of the clip for hearing aid shown in FIG. 1;

FIG. 8 is a perspective view of another embodiment of a clip for hearing aid embodying our design;

FIG. 9 is a side elevational view of the clip for hearing aid shown in FIG. 8;

FIG. 10 is a rear view of the clip for hearing aid shown in FIG. 8;

FIG. 11 is a top view of the clip for hearing aid shown in FIG. 8;

FIG. 12 is an opposite side elevational view of the clip for hearing aid shown in FIG. 9;

FIG. 13 is a bottom view of the clip for hearing aid shown in FIG. 8;

FIG. 14 is a front view of the clip for hearing aid shown in FIG. 8;

FIG. 15 is a perspective view of yet another embodiment of a clip for hearing aid embodying our design;
FIG. 16 is a side elevational view of the clip for hearing aid shown in FIG. 15;
FIG. 17 is a rear view of the clip for hearing aid shown in FIG. 15;
FIG. 18 is a top view of the clip for hearing aid shown in FIG. 15;
FIG. 19 is an opposite side elevational view of the clip for hearing aid shown in FIG. 16;
FIG. 20 is a bottom view of the clip for hearing aid shown in FIG. 15;
FIG. 21 is a front view of the clip for hearing aid shown in FIG. 15;

FIG. 22 is a perspective view of yet another embodiment of a clip for hearing aid embodying our design;
FIG. 23 is a side elevational view of the clip for hearing aid shown in FIG. 22;
FIG. 24 is a rear view of the clip for hearing aid shown in FIG. 22;
FIG. 25 is a top view of the clip for hearing aid shown in FIG. 22;
FIG. 26 is an opposite side elevational view of the clip for hearing aid shown in FIG. 23;
FIG. 27 is a bottom view of the clip for hearing aid shown in FIG. 22; and,
FIG. 28 is a front view of the clip for hearing aid shown in FIG. 22.
